C. G. HARTLEY,
GOVERNOR FOR TRACTOR ENGINES,
APPLICATION FILED SEPT. 25, 1919.

1,409,170.

Patented Mar. 14, 1922.

UNITED STATES PATENT OFFICE.

CALVIN GLENN HARTLEY, OF ROANOKE, INDIANA, ASSIGNOR TO KNOX ENGINEERING AND MANUFACTURING COMPANY, A CORPORATION OF INDIANA.

GOVERNOR FOR TRACTOR ENGINES.

1,409,170.

Specification of Letters Patent. Patented Mar. 14, 1922.

Application filed September 25, 1919. Serial No. 326,373.

To all whom it may concern:

Be it known that I, CALVIN GLENN HARTLEY, a citizen of the United States of America, and resident of Roanoke, in the county 5 of Huntington and State of Indiana, have invented certain new and useful Improvements in Governors for Tractor Engines, of which the following is a specification.

This invention relates to improvements 0 in governors for tractor engines, and the object thereof is to provide an automatic governing device in conjunction with a controlling lever for adjusting the governing device and which will also serve as a manual 5 control for the engine.

The object of the invention is accomplished by the construction illustrated in the accompanying drawings in which Fig. 1 is a side elevation of the invention supported in place on an engine body, partially broken away and in section; and Fig. 2 is a detail view showing an oscillating shaft and levers mounted thereon. Having reference now to the various parts of the 5 invention indicated by characters appearing upon the drawings:

1 is an engine body of known construction, and 2 is a belt pulley of the usual type ordinarily used for driving the fan 0 of the radiator (not shown), the pulley being fixed upon the front end of the engine crank-shaft 3. Upon the hub 4 of the pulley are oppositely positioned lugs 5 in which are pivotally supported corresponding levers 6, each of which has upon its inner end a weight 7, the weights being coupled together at their ends by a tension spring 8. The outer ends of the respective levers 6 bear against a ring 9 upon the adjacent side thereof, and the opposite side of the ring is adapted to bear against the ends of a forked lever 10 that is fixed upon a shaft 11 mounted in a bracket 12 on the engine body, so that as the weights spread apart the shaft 11 is accordingly turned through the medium of the levers 6, ring 9 and forked lever 10.

Upon the shaft 11 is also fixed an arm 13 and to the outer end thereof is connected the throttle valve (not shown) of the engine, which is of the usual type, by means of a throttle rod 14 so arranged that the valve is closed to a more or less extent accordingly as the arm swings upwardly.

An intermediate lever 15 is fixed on the

shaft 11 and an operating lever 16 is pivoted at its middle to a bracket 17 having a sector 18 thereon. A rod 19 is connected to the lower end of the intermediate lever 15 and extends loosely through the lower 60 end of the operating lever 16 and has a wing-nut 20 thereon against which the operating lever is adapted to bear and move the rod in one direction. The rod being loose in the operating lever admits of its 65 longitudinal movement in the lever in one direction and the wing-nut limits the movement of the rod in the opposite direction by coming into contact with the operating lever. By turning the wing-nut on the 70 rod the stage at which its movement is limited may be adjustably fixed.

To the upper end of the intermediate lever 15 is secured one end of a tension spring 21, the other end of which is secured 75 to an actuating rod 22 that is secured at its opposite end to the upper part of the operating lever 16. The other end of the spring 21 is connected to the actuating rod 22 by any suitable means, such as a block 80 23. The corresponding end of the rod 22 extends longitudinally through the spring 21 and terminates with a hook 24 by means of which the expansion of the spring is limited in extent.

In the operation of the invention, as the engine revolves the pulley 2, the weights 7 spread to a more or less extent according to the velocity thereof and the ring 9 is correspondingly moved rearwardly by 90 the consequent action of the levers 6 and the forked lever bearing against the opposite side of the ring is therefore actuated, causing the shaft 11 and arm 13 to oscillate, thus affecting the throttle-valve of the engine so that the speed of the engine is regulated. The intermediate lever 15 also is oscillated, which movement is resisted by the tension spring 21. By adjustably positioning the operating lever the forked 100 lever 10 and arm 13 may be initially set so as to become affected by the movement of the ring 9 at any desired stage and thus the fuel admitted to the engine through the throttle valve is reduced when the pre-determined velocity is reached. By manipulating the operating lever the throttle-valve is actuated irrespective of the behavior of the weighted levers in the pulley 105 and thus the engine is manually controlled 110

independently of the action of the automatic governing mechanism.

What I claim is:

1. In combination with an engine including a throttle-rod and a governing mechanism including revolving weighted levers and a bearing ring actuated by the levers, an oscillating shaft suitably mounted; a forked lever fixed on the shaft and having actuated relation with the ring; an arm fixed on the shaft having connection with the throttle-rod; an operating lever and sector therefor; an intermediate member fixed on the shaft; a rod connected to the lower end of the intermediate member and extending loosely through the lower end of the operating lever and having limiting means thereon to engage the lever; a tension spring connected at one of its ends to the upper end of the intermediate member; and a rod having connection with the upper end of the operating lever and also with the other end of the spring.
2. In a controlling means for engines having a throttle-rod, weighted governor

levers and a bearing ring actuated by the levers, an oscillating member bearing against the ring and adapted to actuate the throttle-rod; an intermediate member having fixed relation with the oscillating member; an operating lever including a lever and sector; an adjustable connecting means between the operating lever and the intermediate lever; a tension spring, one end of which is connected to the intermediate lever opposite the connecting means; and a rod secured at one end to the operating lever opposite the connecting means and having fixed connection with the other end of the tension spring, said rod extending through the tension spring and terminating with a hook adapted to limit the action of the spring.

In testimony whereof I affix my signature, in presence of two witnesses.

C. GLENN HARTLEY.
